UNITED STATES PATENT OFFICE.

HUDSON R. MEYERS, OF NEW HAVEN, CONNECTICUT.

DESIGN FOR A MINIATURE HONOR-BOARD.

53,204.

Specification for Design.

Patented Apr. 15, 1919.

Application filed January 14, 1919. Serial No. 271,151. Term of patent 3½ years.

To all whom it may concern:

Be it known that I, HUDSON R. MEYERS, a citizen of the United States, residing at New Haven, in the county of New Haven and State of Connecticut, have invented a new, original, and ornamental Design for a Miniature Honor-Board, of which the following is a specification, reference being had to the accompanying drawing, forming part thereof.

The figure is a perspective view of a miniature honor board, showing my new design.

I claim:

The ornamental design for a miniature honor board, as shown.

HUDSON R. MEYERS.

Witnesses:

FREDERIC C. EARLE,
CLARA L. WEED.
